[57] CLAIM

The ornamental design for a chamber for a vacuum cleaner, as shown and described.

DESCRIPTION

FIG. 1 is a front and side perspective view of a chamber for a vacuum cleaner showing our new design;
 FIG. 2 is a top plan view thereof;
 FIG. 3 is a right side elevational view thereof;
 FIG. 4 is a left side elevational view thereof;
 FIG. 5 is a front elevational view thereof;
 FIG. 6 is a front and side perspective view of second embodiment thereof;
 FIG. 7 is a top plan view thereof;
 FIG. 8 is a right side elevational view thereof;
 FIG. 9 is a left side elevational view thereof;
 FIG. 10 is a front elevational view thereof;
 FIG. 11 is a front and side perspective view of third embodiment thereof;
 FIG. 12 is a top plan view thereof;
 FIG. 13 is a right side elevational view thereof;
 FIG. 14 is a left side elevational view thereof;
 FIG. 15 is a front elevational view thereof;
 FIG. 16 is a front and side perspective view of fourth embodiment thereof;
 FIG. 17 is a top plan view thereof;
 FIG. 18 is a right side elevational view thereof;
 FIG. 19 is a left side elevational view thereof; and,
 FIG. 20 is a front elevational view thereof.
 The portion of the vacuum cleaner shown in broken lines in all views is for illustrative purposes only and forms no part of the claimed design.
